UNITED STATES PATENT OFFICE

SALVATORE J. FARANDA, OF EAST ELMHURST, NEW YORK

CIGARETTE HOLDER

Application filed June 24, 1927. Serial No. 201,086.

This invention relates to holders for cigarettes and cigars. It is contemplated that the invention will be chiefly used for cigarettes and it will, therefore, be described and claimed herein as a cigarette holder, but the word "cigarette" as hereinafter used, is not intended to have a narrow meaning, but is intended to include cigars, also, except where the context plainly indicates that the word is used in a more limited sense.

The smoking of cigarettes is at times, at least, attended with inconvenience, discomfort, and embarrassment, results in untidiness and litter, and, if the smoker is careless, is likely to result in burning or charring of furniture or clothing, or in personal injury or in starting a conflagration.

The present invention has for its object to provide means to substantially diminish or avoid these objectionable features. To this end it is a feature of the invention that provision is made of a cigarette holder having a guard or container for surrounding the cigarette which will effectively prevent spilling of the ashes from the cigarette tip, will obviate the necessity for knocking the ashes off into an ash tray at frequent intervals, and will guard the cigarette from contact with other objects which it might injure, or which might knock out the light.

It is a further object of the invention to provide such guard or container with a cover operable between a position to partially open the container and admit air thereto and a position to close the container and thereby extinguish the cigarette. This feature has several advantages. It avoids the likelihood of a burning cigarette being thrown down hurriedly in a place where it might start a conflagration. It also results in economy to the smoker, and particularly in conserving cigarettes when the available supply is limited, since partially consumed cigarettes can be saved for future use.

Other objects and advantages will herein-after appear.

In the drawings forming a part of this specification:

Figure 1 is a side elevation of a cigarette holder embodying features of the invention,

and shows the container in closed position;

Figure 2 is a view similar to Figure 1, showing the container in open position, as it would be when the cigarette is being smoked;

Figure 3 is an enlarged, fragmentary, longitudinal, central, vertical section;

Figure 4 is a transverse, vertical section on the line 4-4 of Figure 3, looking in the direction of the arrows; and

Figure 5 is a view similar to Figure 4, showing the container in open position.

The cigarette holder comprises a mouthpiece 1 having a passage 2 therethrough which is enlarged at its outer end to receive the end of a cigarette 3. The outer end of the mouthpiece is reduced slightly to form a shoulder 4, and the reduced end 5 of the mouthpiece is externally threaded, preferably with a multiple thread of steep pitch.

Provision is made of a cigarette guard and container 6 in which the cigarette 3 is adapted to lie while being smoked. The container, in the illustrative form of the invention, comprises a cylindrical barrel 7 of wood, briar, amber, or other suitable material which is internally threaded at one end for detachable securement to the reduced threaded end 5 of the mouthpiece. Except at the ends thereof, the barrel 7 has a considerable segment cut away along one of its sides to form an opening 8, through which air may be admitted to the lighted cigarette.

When the cigarette is being smoked, it is, of course, necessary to admit air to the barrel, and the opening 8 is therefore uncovered. When it is desired to put the cigarette holder away, however, and conditions are such that no proper disposition can be made of the cigarette and ashes in the holder, it is desirable to cover the opening 8 so that the container may be used for the storage of the cigarette and the ashes and may be carried in the pocket until a suitable opportunity for disposing of the cigarette and the ashes occurs.

To this end provision is made of a sleeve 9 rotatably mounted on the barrel 7. The sleeve 9 has a considerable segment cut away completely along one side, except at the ends of the sleeve to form an opening 10 of slight

ly larger dimensions than the opening 8 of the barrel. The sleeve 9 may be rotated on the barrel 7 to a position to cover the opening 8 of the barrel completely or to a position 5 to bring the opening 10 of the sleeve into registration with the opening 8. The rotation of the sleeve 9 to close the opening 8 is effective not only to prevent spilling of 10 ashes from the container, but also to exclude air from the container, and therefore to extinguish the cigarette quickly.

When a cigarette is smoked in the holder • as described, the tobacco is burned completely, but approximately all of the lower 15 half of the paper remains unburned. The ashes adhere to this unburned paper and are not readily shaken out, even when the holder is inverted. When it is desired to remove the old cigarette, however, and the barrel 7 20 is unscrewed from the mouthpiece 1, the cigarette butt adhering to the mouthpiece withdraws the entire length of unburned paper together with the contained ashes from the barrel, and leaves the barrel clean 25 and unobstructed for the reception of a fresh cigarette.

Due to the protection to the barrel afforded by the unburned paper, the barrel does not become substantially charred or caked, and 30 cleaning is seldom necessary. As a cigarette may occasionally become jammed in the barrel, however, provision is made of a removable plug 11 in the end of the barrel 7 remote from the mouthpiece 1. When it is necessary to clean the barrel, the plug 11 and the mouthpiece 1 are removed from the barrel 7 and the barrel is then cleaned by thrusting a suitable rod or other cleaner through it.

While, as has been stated, the barrel 7 does 40 not char substantially, there is a very slow charring and eating away of the barrel along the edges of the opening 8. This eating away of the barrel may occur more rapidly at one end of the barrel than the other. In order 45 to prolong the useful life of the container, it may be desirable to reverse the container end for end. Accordingly, the end 12 of the plug 11 is threaded in exactly the same manner as the end 3 of the mouthpiece 1, so 50 that the plug and mouthpiece can be interchanged, if desired.

In using the invention, the smoker first unscrews the container 6 from the mouthpiece 1, inserts a cigarette in the mouthpiece, 55 and then threads the mouthpiece into the barrel 7. The opening 8 in the barrel 7 is long enough to extend a little beyond the end of a cigarette so that a match may be applied at the far end of the opening 8 for 60 lighting the cigarette.

Should the smoker desire to lay his cigarette down while lighted, there is no danger of marring furniture, since the cigarette cannot come into contact with the 65 object on which it is laid. Small bosses 13

may be pressed outward on the sleeve 9 to prevent the holder from rolling when thus laid down.

While I have illustrated and described in detail certain preferred forms of my invention, it is to be understood that changes may be made therein and the invention embodied in other structures. I do not, therefore, desire to limit myself to the specific constructions illustrated, but intend to cover my invention broadly in whatever form its principle may be utilized.

I claim:

1. In a cigarette holder, the combination with a mouthpiece, of a barrel forming a prolongation of the mouthpiece in which the cigarette is adapted to lie, said barrel having an opening along one side thereof and a sleeve rotatably mounted on the barrel, said sleeve being open along one side thereof and being rotatable to a position for admitting air to the barrel or to a position for excluding air therefrom.

2. In a cigarette holder, in combination, a cigarette containing barrel, a mouthpiece detachably connected to one end of the barrel, a removable plug closing the opposite end of the barrel, said barrel having an opening along one side thereof, and a member rotatably mounted on the barrel and operable to cover and uncover the opening in the side of the barrel as desired.

3. In a cigarette holder, the combination with a mouthpiece, of a cigarette containing barrel detachably secured thereto, a sleeve on the barrel, said barrel and sleeve each having an opening along one side thereof, the sleeve being rotatable on the barrel to cover and uncover the barrel opening, and a removable plug closing the end of the barrel remote from the mouthpiece.

4. In a cigarette holder, in combination, a cigarette containing barrel open along one side, and a cover sleeve journaled on the barrel coaxially therewith and rotatable relative thereto to cover and uncover said open side as desired.

In testimony whereof I have affixed my signature to this specification.
